UNITED STATES PATENT OFFICE

JOSEPH GOUGH, OF NEWARK, NEW JERSEY, ASSIGNOR TO GOUGH STEMMING MACHINE CORPORATION, OF NEW YORK, N. Y., A CORPORATION OF NEW JERSEY

STEMMING APPARATUS

Application filed May 18, 1928. Serial No. 278,697.

My invention relates to leaf stemmers of the type shown in my co-pending application Serial No. 49,208, filed on or about August 10, 1925, that is to say stemmers in which the stems are grasped by and between moving belts at the stemming station.

These stemming belts are driven belts, and usually one is driven by gear wheels connecting the two belts. It has been found however, that the dirt and other foreign matter in and about tobacco stemming machines, wear the teeth of these interconnecting gears both rapidly and severely, thus loosening up the driving connection of the belt driven thereby and to a certain extent stems escape from the belts usually from between the edges of the belts facing the exit end of the machine, before being completely extracted from the leaf blades.

The object of my invention is to improve machines of this type in the respect indicated. The manner in which this is accomplished appears from the description of a machine embodying my present invention, which follows.

The accompanying drawings illustrate my invention applied to a stemming machine quite like that illustrated in my co-pending application above identified. For the sake of simplicity and clarity, various parts commonly found on such machines have been omitted from these drawings, as will be understood; substantially only those parts are shown which are necessary for a ready understanding of the invention. Fig. 1 is a plan view of the machine. Fig. 2 is an elevation. Fig. 3 is a sectional view at the stemming belts. Fig. 4 is a broken plan view within the upper belt.

In the machine illustrated, the unstemmed leaves 1, more or less separated from each other, are placed on a series of horizontal belts 2, 3, 4, which carry the leaves to the right in a direction substantially at right angles to the length of the leaves; the guide board 7, against which the ends of the stems of the leaves are laid, serves to indicate the proper placement of the leaves on the belts. These conveyor belts carry the leaves between

two co-operating belts 8 and 9 of, or provided

with, card clothing, that is to say belts having many protruding wires. These form the blade strippers; the stem can be drawn between the wires, but the blades can not follow. These various belts pass over pulleys and supporting surfaces, various of the pulleys of the conveyor belts, and also of the card belt 8, being driven to give motion to the belts; the card belt 9 can also be driven by one of its supporting pulleys in a similar manner, but I have found it quite convenient to let this belt run loose and take its motion from the lower card belt 8 with which its wire teeth more or less intermesh. The co-operating runs of the card belts 8 and 9 travel to the right of the drawing like the conveyor belts and the speed of these two belts may be the same as that of the conveyor belts. The card belts 8 and 9 are so placed that the butt ends of the stems project rearwardly from them, and opposite the card belts and extending back from them, usually substantially in the direction of the stems, are the two co-operating stem-pulling belts 12 and 13. The forward rollers 14 and 15 of these belts substantially face the card belts, and hold the bite of the stem-pulling belts so close to the stripper card belts 8 and 9 that the ends of the stems in moving to the right, enter the bite. Preferably however the rollers 14 and 15 are slightly inclined from parallel to the card belts 8 and 9, and likewise the belts 12 and 13 are slightly inclined from the normal to the plane of the card belts, so that the bite of the belts 12 and 13 is nearer the card belts at the exit side of the machine than at the entrance side, as shown in Fig. 1; this better assures the entry of the stems into the bite of the stem-pulling belts. The stem-pulling belts 12 and 13 are driven in the manner hereinafter described, traveling in the directions of the arrows 16 respectively and are intended to be held so close to each other that stems received between the belts are pulled from the blades, the latter being retained by the card clothing 8 and 9 while the stems are being pulled out, and ultimately discharged at the right hand end, or exit end of the machine. All the belts illustrated may be driven continu-

ously, and thus the stemming may be done while the leaves are travelling from left to right. The stems are thrown out of the stem-pulling belts 12 and 13 to the rear as will be apparent. Devices may be provided to remove the leaf blades from the various belts at the proper places; such devices are well known, and for simplicity none are illustrated in the accompanying drawing.

10 The rolls 20 and 21 support the ends of the belts 12 and 13 remote from the card belts 8 and 9. The roll 20 is driven from the power source of the machine, for example by the sprocket 22 and chain 23, and drives its belt 12; the belt 13 however is driven by friction, and specifically by its frictional engagement with the belt 12. To provide adequate traction for and between these belts for this purpose I make the roller 20 somewhat larger than the lower roller 21, and place it somewhat further to the rear than the roller 21, and somewhat below the top of the roller 21, so that the belt 21 is held in close engagement with the belt 13 throughout an arc of curvature of the belt 13 around its roller 21 (Fig. 3). Thus I eliminate the gear wheels heretofore usually used to connect the two stemming belts for driving purposes. To hold the co-operating stem-engaging runs of 30 the belts close to each other intermediate the two pairs of rollers 14—15 and 20—21, I provide transverse supports 25 and 26, which preferably, are small rollers as indicated. These supports are provided at the edges of 35 the belts from which the leaf blades depart, the right hand edges in the drawings, to assist at this point in preventing the escape from the belts at these edges of long stems or those stems entering the stem-pulling belts late. They need not extend entirely 40 across the belts. Preferably I provide such transverse supports at both edges of the belts as shown. Preferably too the two members 45 25 and 26 of each pair of these transverse supports are not located exactly opposite each other, but are displaced horizontally somewhat from each other (Figs. 3 and 4). Such an arrangement holds the stem-engaging runs of the belts close to each other, or at least 50 prevents undue separation of these two runs from each other so that the stems are gripped firmly, thus tending to successful extraction of the stems and preventing escape of a stem once it has entered between the belts, except at the rear where the completely 55 extracted stems are intended to be thrown out; at the same time the staggered relation of the supports or rolls 25 and 26 of each pair with respect to each other permits extraordi- 60 narily larger stems or foreign matter to pass between the supports without injuring the machine.

The rolls 25 and 26 can be carried on plates 27 within the belts, and these in turn carried 65 by a bracket or brackets 28 fastened to the

brackets supporting the rollers 14, 15, 20 and 21 which carry the stem-pulling belts. To further aid in preventing the escape of stems from the stem pulling belts at the edges of the latter, and especially at those edges which are toward the exit end of the machine (the right hand edges in the drawings), I find it preferable to add a member or members 30 bearing against the edges of belts and spanning the space between the blade-engaging runs of the stem-pulling belts at these edges, preferably vertical rollers as illustrated. These rollers 30 can be carried by the same plates 27 as carry the horizontal rollers 25 and 26. The most important of these edge members is the one located at the right hand edges of the stem-pulling belts, i. e. the edges (from which the blades depart) adjacent the rolls 14 and 15; the other or others at the same edges may also act directly to assist in keeping stems from escaping through these edges, and also to guide the stem-pulling belts in their proper paths. The members 30 at the opposite or left hand edges assist the same action by keeping the belts 12 and 13 against the members 30 at the right.

Desirably cover plates 31 are provided to enclose the top and two sides of the belts 12 and 13, and the ends of the rollers supporting with these belts so far as possible. The purpose of these cover plates is to prevent the entrance of foreign matter, and especially the accidental or deliberate insertion of leaf stems or other foreign matter into the belts where they pass around the supporting rollers.

It is to be understood that my invention is not limited to the details illustrated and described, except as appears hereinafter in the claims.

I claim:

1. In a stemming machine blade-stripping means, a pair of belts co-operating to receive the stems between them for extraction from the blades, and means for driving one of said belts, the other belt being driven frictionally from said driven belt.
2. In a stemming machine, means for retaining the leaf blades, a pair of belts co-operating to receive the stems between them and pull the stems from the blades, a belt support within one of said belts around which said belt is curved, the other of said belts engaging said one of the belts throughout an arc of the curvature of the latter around said support to provide traction for driving one of the belts from the other, and means for driving one of said belts.
3. In a stemming machine, means for retaining the leaf blades, a pair of co-operating belts extending away therefrom in the general direction of the leaf stems and arranged to receive the stems and pull the stems from the blades, means to support said belts adja-

cent said blade-retaining means, a belt support around which one of said belts is curved at a point more remote from said blade-retaining means, and a belt support for the 5 other of said belts, the last mentioned two belt supports being so related that the last mentioned belt is held in engagement with the first mentioned belt throughout an arc of the curvature of the first mentioned belt around 10 its said remote support to provide driving traction on one of the belts, and means for driving one of said belts, the other being driven by its engagement with the driven belt.

15 4. In a stemming machine, continuously moving means moving with the leaves in a direction substantially at right angles to the leaves and for retaining the blades of the leaves as the stems are pulled out, a pair of co-operating belts extending away from said means in the general direction of the leaf stems and arranged to receive the stems and pull the stems from the blades, means to support the belt adjacent said blade retaining 20 means, a pulley more remote from the blade-retaining means within one of the belts and around which said belt is curved, a pulley engaging the other belt, said pulleys being so arranged that the second mentioned belt 25 is held in engagement with the first mentioned belt throughout an arc of the curvature of the first mentioned belt around the said pulley within it to afford traction between the belts, and means for driving a pulley supporting one of said belts, the other belt being driven by its engagement with the belt on the driven pulley.

30 5. In a stemming machine, continuously moving means moving with the leaves in a direction substantially at right angles to the leaves and for retaining the blades of the leaves as the stems are pulled out, a pair of co-operating belts extending away from said means in the general direction of the leaf stems and arranged to receive the stems and pull the stems from the blades, means to support the belt adjacent said blade-retaining means, a pulley more remote from the blade retaining means within one of the belts and 35 around which said belt is curved, a pulley engaging the other belt, said pulleys being so arranged that the second mentioned belt is held in engagement with the first mentioned belt throughout an arc of the curvature of the first mentioned belt around the said pulley within it to afford traction between the belts, means for driving a pulley supporting one of said belts, the other belt being driven by its engagement with the belt on the driven 40 pulley, rolls within and transverse of the belts between said belt-supporting means and said pulleys, to hold the stem-engaging runs of the two belts close to each other intermediate said supporting means and rolls trans- 45 verse to the edges of the belts bearing against

the edge of the said stem-engaging runs of the two belts.

5 6. In a stemming machine, means for retaining the leaf blades, a pair of belts co-operating to receive the stems between them and pull the stems from the blades, means to support the belts adjacent said blade-retaining means, means to support the belts substantially close to each other at a point more remote from said blade-retaining means, and rolls transverse to the belts between said two belt-supporting means to hold the stem-engaging runs of the belts close to each other intermediate said supporting means for the belts.

70 7. In a stemming machine, means for retaining the leaf blades, a pair of belts co-operating to receive the stems between them and pull the stems from the blades, means to support the belts adjacent said blade-retaining means, means to support the belts substantially close to each other at a point more remote from said blade-retaining means, and means between said two belt-supporting means to hold the stem-engaging runs of the belt close to each other intermediate said belt supporting means.

75 8. In a stemming machine, means for retaining the leaf blades, a pair of belts co-operating to receive the stems between them and pull the stems from the blades, means to support the belts adjacent said blade-retaining means, means to support the belts substantially close to each other at a point more remote from said blade-retaining means, a belt-engaging member within each of said belts between said two belt-supporting means, said members co-operating to hold the stem-engaging runs of the belts close to each other and said members not being opposite each other.

80 9. In a stemming machine, continuously moving means moving with the leaves in a direction substantially at right angles to the leaves and arranged to retain the leaf blades as the stems are pulled out, a pair of co-operating belts extending away from said means in a direction substantially parallel with the leaf stems to receive the stems between them and pull the stems from the leaves, and means spanning the space between the blade-engaging runs of the belts at the edges thereof from which said blade-retaining means moves away, to prevent the escape of the leaf stems from the belt at said edges.

85 10. In a stemming machine, blade-retaining means continuously moving with the leaves in a direction substantially at right angles to the leaves, a pair of belts extending away from said blade-retaining means in a direction substantially parallel to the leaf stems and co-operating to receive the leaf stems between them and draw the stems from the blades, means to support the belts adja- 90

cent said blade-retaining means, means to support the belts close to each other at a point more remote from said blade-retaining means, a roll within each belt, each roll holding the stem-engaging run of its belt at the edge thereof from which said blade-retaining means moves away toward the stem-engaging run of the other belt at a point intermediate said supports, said rolls being displaced from each other, and a member spanning the space between the blade-engaging runs of the belts at said edges thereof, to prevent escape of stems from the belts at said edges.

In testimony whereof, I have signed this specification.

JOSEPH GOUGH.
